UNITED STATES PATENT OFFICE.

MARION E. VAUGHN, OF PLAINFIELD, INDIANA.

EXCESSIVE-ELECTRICAL-CURRENT ARRESTER.

982,551.

Specification of Letters Patent. Patented Jan. 24, 1911.

Application filed August 9, 1909. Serial No. 512,066.

To all whom it may concern:

Be it known that I, MARION E. VAUGHN, of Plainfield, county of Hendricks, and State of Indiana, have invented a certain new and useful Excessive - Electrical - Current Arrester; and I do hereby declare that the following is a full, clear, and exact description thereof, reference being had to the accompanying drawings, in which like letters refer to like parts.

The object of this invention is to provide a very simple, cheap and yet efficient device for arresting lightning, or diverting to the ground an excessive charge of electricity. It is particularly arranged and adapted for use in connection with telephones, telegraphs and the like.

The nature of the invention will be understood from the accompanying drawings and the following description and claims.

In the drawings Figure 1 is a side elevation of the device mounted in connection with conductors partly broken away. Fig. 2 is a central vertical section through the device on the same plane as the main conductor. Fig. 3 is a plan view of the lower half of the device. Fig. 4 is a vertical section through the device centrally and transversely of Fig. 2 and with the casing and downwardly extending conductor removed. Fig. 5 is a plan view of a sheet of mica or other insulation.

The device consists of two halves formed very much alike, and between which the main conductor 10 lies. The current normally passes through this conductor. In telephones, telegraphs, and the like, the normal current is a weak one as compared with the heavy voltage of a current caused by lightning or the contact of the main conductor 10 with a conductor carrying a current of very high voltage. A conductor 11 running to the ground is arranged in such proximity to the main conductor 10 that any excessive charge of voltage of current will jump from the main conductor and short-circuit it to the conductor 11 and the ground, and thus protect instruments such as telephones, and the like, connected with the main conductor.

The device includes an upper cup-like casing 12 and a lower cup-like casing 13 preferably cylindrical in form and with the open sides of said casing meeting each other, the upper end of the lower casing fitting within an enlarged flanged overlapping portion

14 of the upper casing. This overlapping portion 14 is provided with slots 15 on opposite sides and opening downwardly and wide enough to receive the main conductor 10. Said conductor 10 is insulated by the insulation 16 from the casing. The two halves 12 and 13 of the casing are clamped together and on the main wire 10 by screws 17 passing through the ears 18 on the upper casing 12 and screwing into the ears 19 projecting laterally from the lower casing 13 through a notch or recess 20 in the lower edge of the upper casing 12.

Within the upper casing 12 there is a round carbon block 21 and a corresponding carbon block 22 in the lower casing. This latter carbon block has a central downwardly extending hole through it in which a copper tube 23 is secured and in which the ground conductor 11 fits, and said conductor is held in place by the screw 24 that extends through a projection 25 in the lower end of the casing 13. The copper tube 23 effects a good electrical connection between the carbon block 22 and the ground wire 11.

A pair of copper disks 26 are placed on the main conductor 10, one on each side thereof and they are centrally grooved in order to fit around said conductor snugly, as indicated in Figs. 2 and 4. They are very thin disks, and between each of said disks and the carbon blocks 21 and 22 above and below the same, a perforated insulation disk 27 is located. This is ordinarily made of mica and is rather thin, it being shown relatively thicker in Figs. 2 and 4 than it should be, in order to plainly indicate it.

During travel of an ordinary current through the main wire 10, there would be no disposition on the part of the current to jump from said wire to the carbon blocks because the perforated insulating disk 27 holds said blocks 21 and 22 sufficiently away from the copper disks 26, but if a large enough charge of current is passing through the conductor 10 to cause it to jump the short distance from the copper disks 26 to the carbon blocks 21 and 22, such current will largely, if not entirely, short-circuit to the ground. Hence the thickness of the insulating disk 27 may be varied to suit the position of use of the device for the voltage of current passing through the same. When the current jumps from the conductor 10 and copper disks 26 to the carbon blocks it passes through the perforations or holes

in the insulating disk 27. By providing said disk with a large number of such holes and by the relatively extended surface of said disk and the copper plates 26, there 5 would be ample opportunity for any excess of voltage to jump to the carbon blocks.

When used in connection with telephones, any lightning current will pass to the ground through this device instead of to the 10 telephone in the residence, and after such incident has occurred, this lightning arrester will still be in normal working condition, so that the device does not have to be replaced or given attention after lightning 15 or high voltage has passed through it to the ground. No further attention is necessary than what is required at long intervals to keep the device in general working order. This feature of use coupled with the simple 20 and economical construction of the device renders it on the whole an extremely cheap yet effective lightning arrester.

What I claim as my invention and desire to secure by Letters Patent is:

25 1. A device of the class described including a main conducting wire, a carbon block on each side thereof, insulation between the carbon blocks and wire so as to space the blocks from the wire, means for clamping 30 the blocks and insulation to the wire, and a ground wire running from one of the carbon blocks to the ground.

2. A device of the class described including a casing formed of two cup-like halves, 35 adapted to place a main conductor, insulation between said casing and a main con-

ductor, a carbon block in each half of the casing and on each side of the main conductor, a disk of conducting material on each side of the main conductor, a disk of insulating material between each carbon block and disk of conducting material, and a conductor running from the casing to the ground.

3. A device of the class described including a casing formed of two cup-like halves, 40 one enlarged to overlap the other and the enlarged portion of said overlapping part of the casing being slotted on opposite sides so that said parts of the casing may embrace 45 a main conductor, means in said slots for insulating said casing from the main conductor, means for clamping the two parts of the casing together, a disk of conducting material adapted to be placed on each side 50 of the main conductor, a carbon block in each half of the casing, one of them centrally apertured, a perforated disk of insulating material between each carbon block and the disk of conducting material, a tube 55 fixed in the aperture of one of said carbon blocks and made of conducting material, and a conductor fitting in said tube in communication with the ground.

In witness whereof, I have hereunto af- 60 fixed my signature in the presence of the 65 witnesses herein named.

MARION E. VAUGHN.
